GARMENT BAG

Filed July 26, 1927

Inventor:
Adolph Potdevin
by his Attorney
John O. Nolan

UNITED STATES PATENT OFFICE.

ADOLPH POTDEVIN, OF GARDEN CITY, NEW YORK, ASSIGNOR TO POTDEVIN MACHINE COMPANY, OF BROOKLYN, NEW YORK, A CORPORATION OF NEW YORK.

GARMENT BAG.

Application filed July 26, 1927. Serial No. 208,481.

This invention relates to suspension garment bags, having reference more especially to the type of bags, termed "dry cleaner bags", which are largely used by dry cleaning establishments as a temporary protective covering for dresses, coats and other garments that have been cleaned.

Bags of this type, as heretofore constructed, comprised a large flattened tube of paper having its upper end diagonally folded in opposite directions from points adjacent the center of the bag, the folds thus formed being pasted to the body of the bag and constituting a reinforcing closure having a central opening for the passage of the suspension hook of a contained hanger from which a garment was suspended within the confines of the bag. In using such bags the garment was first suspended on the hanger, and the whole was then introduced in the bag by way of the open bottom. This was a difficult operation, particularly in the case of large garments, because unless the paper bag were extraordinarily stout much care was required to insert therein the hanger and garment, as otherwise the lateral edges or sides of the bag would be torn.

The principal object of my invention is to provide a suspension garment bag of simple and economical construction having one side thereof so formed that it can be readily opened throughout its length to facilitate the entry in the bag, or the removal therefrom, of the garment and its hanger, and such side can then be readily closed, and be held in closed position by suitable clips.

Another object of my invention is to provide the front of the bag with a transparent or translucent panel which facilitates the identification of the contents of any particular bag in service, as occasion may require.

According to the preferred embodiment of my invention the bags are made successively from a flat tubular web whereof one side is longitudinally slit at regular intervals to provide in each bag length an opening extending from the bottom portion to a point at or near the outer fold line for the adjacent diagonal top fold, thereby ensuring

the uniform relation of the front and back of the tubular web during its progress to the bag making instrumentalities, and at the same time preserving the integrity and strength of the top fold when the bag is formed.

The invention also comprises novel features of construction which will be herein-after described and claimed.

In the drawings—

Figure 1 is a perspective view, from the front, of a garment bag embodying my invention.

Fig. 2 is a similar view, from the back, of said bag, a garment hanger being associated therewith, and one corner of the bag being torn away to expose concealed parts.

Fig. 3 is a similar view, from the front, of the laterally slitted pliated blank before the formation of the diagonal top folds, the lines of such folds being indicated.

Fig. 4 is a front elevation of the complete bag, showing its open side as closed and secured by clips, a portion of the front being broken away to expose one corner of the translucent panel.

The bag herein illustrated comprises a front and a back 5, 6, respectively; bellows-fold sides 7; an open bottom 8, and two diagonal top folds 9, 10 which are downwardly inclined from points adjacent the mid-section of the top to the respective sides of the bag. These folds are pasted to the back of the bag to produce therefor a top closure having a central opening 11 through which is adapted to extend an upstanding suspension hook, as 12, of a contained hanger 13 designed to sustain a garment within the confines of the bag. The bag is made from a single sheet of paper which is appropriately shaped and folded to present a median longitudinal seam 14 on the back; and one side of the bag is longitudinally slit midway between the front and back, as at 15, from the bottom to a point, as 16, at the outer end of the superposed plies of the adjacent fold 9, thus producing lateral flaps 17, 18. The flap 17 may be pasted to the front of the bag to afford a marginal reinforcement therefor and the flap 18 may be

folded over upon the reinforced margin of the front so as to afford a closure flap for the adjacent open side of the bag.

From the foregoing it will be seen that the slotted side of the bag can be readily opened throughout its length to facilitate the entry in the bag of a garment and its hanger, which side can then be closed by the marginal flap 18 and be held in closed condition by the application of suitable clips, as 19, or other fasteners. By a reverse operation the side of the bag can be released and opened, and the garment and its hanger can then be readily removed from the bag.

It will also be seen that by terminating the longitudinal slit in the region of the diagonal top fold 9 the strength of the bag at this location is unimpaired. This is a distinct advantage since the shoulder portion of the bag while in service is subjected to much stress and wear.

In the production of bags embodying my invention the bag lengths are successively severed from a flat tubular web having one side longitudinally slotted at regular intervals to provide the requisite side opening for the bag when it is subsequently completed by the top folding operation. Hence, the uniform relation of the front and back of the plicated web is maintained during its progress to the cutting and end folding mechanism of the bag making machine.

As a simple and efficient means to facilitate the identification of the contents of the bag, the front of the latter is cut out, as at 20, and the opening thus formed is closed by means of a panel 21 of celluloid or other translucent or transparent material which is pasted along its edges to the inner surface of the front portion. This operation is preferably performed at properly spaced intervals throughout the length of the sheet of paper stock preparatory to the tubular formation of the latter.

While I have herein illustrated my invention as embodied in a bag of the bellows side type, it is to be understood that the invention in its broader aspect includes other types of bags.

I claim—

1. A garment bag comprising a flat tubular body whereof the front and back walls are separated at one side from the bottom to a point below the top of the body, thus providing an open side having a connecting portion at its upper end, said walls having oppositely-inclined top folds which overlap and adhere to one of said walls, thus constituting a reinforcing closure having an opening at the apex of the folds, and one of said folds including the connecting portion at the upper end of the open side of the body.

2. A garment bag comprising a flat tubu-

lar body whereof the front and back walls are separated at one side from the bottom to a point below the top of the body, thus providing an open side having a connecting portion at its upper end, the free marginal edge of one of said walls being extended to provide a longitudinal flap foldable upon the adjacent marginal edge of the other wall, said walls having oppositely-inclined top folds which overlap and adhere to one of said walls, thus constituting a reinforcing closure having an opening at the apex of the folds, and one of said folds including the connecting portion at the upper end of the open side of the body.

3. A garment bag comprising a flat tubular body whereof the front and back walls are separated at one side from the bottom to a point below the top of the body, thus providing an open side having a connecting portion at its upper end, the free edges of said walls being extended to provide foldable marginal portions, said walls having oppositely-inclined top folds which overlap and adhere to one of said walls, thus constituting a reinforcing closure having an opening at the apex of the folds, and one of said folds including the connecting portion at the upper end of the open side of the body.

4. A garment bag comprising a flat tubular body whereof the front and back walls are separated at one side from the bottom to a point below the top of the body, thus providing an open side having a connecting portion at its upper end, the free edges of said walls being extended to provide foldable marginal portions, one of which portions is secured to the adjacent wall to reinforce the edge thereof, and the other of which portions is foldable upon the said reinforced edge, said walls having oppositely-inclined top folds which overlap and adhere to one of said walls, thus constituting a reinforcing closure having an opening at the apex of the folds, and one of said folds including the connecting portion at the upper end of the open side of the body.

5. A garment bag comprising a flat tubular body having front and back walls with bellows sides, one of which sides is longitudinally divided from the bottom to a point below the top of the bag, thus providing an open side having a plicated connecting portion at its upper end, said walls having oppositely-inclined top folds which overlap and adhere to one of said walls, thus constituting a reinforcing closure having an opening at the apex of the folds, and one of said folds including the connecting portion at the upper end of the open side of the body.

6. The method of making garment bags having diagonal top folds with a central opening therebetween, comprising making a

flat tubular web from which a plurality of bag lengths can be severed, slitting one side of said web longitudinally at regular intervals to provide in each bag length severed from the web an opening extending from the bottom portion to a point at the outer fold line for the adjacent diagonal top fold, then folding the diagonal top folds against and securing them to one of the walls of the bag. Signed at New York in the county of ¹⁰ Kings and State of New York this 22 day of July, A. D. 1927.

ADOLPH POTDEVIN.
